UNITED STATES PATENT OFFICE.

GUSTAVE HUMBER, OF DENVER, COLORADO.

LANTERN.

1,414,414.

Specification of Letters Patent. Patented May 2, 1922.

Application filed June 26, 1919. Serial No. 306,771.

To all whom it may concern:

Be it known that I, GUSTAVE HUMBER, a citizen of the United States, residing at Denver, county of Denver, and State of Colorado, have invented certain new and useful Improvements in Lanterns, of which the following is a specification.

My invention relates to lanterns, and particularly to lanterns especially adapted for 10 use by railway men for giving signals.

The object of my invention is to provide a device of the class described by means of which either red or white signals may be given without necessitating the change of 15 any of the parts of the device. A further object of my invention is to provide a device as mentioned which shall be as readily handled as the ordinary signal lantern. Other objects will appear hereinafter.

With these objects in view, my invention 20 consists generally in a body portion adapted to contain an electric battery, a pair of lamps on said body adapted to give different colored signals when energized, a handle, and a

switch for selectively energizing either of 25 said lamps as desired. My invention further consists in a device as mentioned in which the lamps are arranged on opposite sides of the body portion so that the light from one 30 will not deflect upon the other, thereby avoiding giving a false signal. My invention further consists in a device as mentioned in which the switch is arranged on the handle 35 of the device in convenient position to be operated by the thumb of the hand grasping the handle. My invention further consists in various details of construction and arrangements of parts all as will be fully described hereinafter and particularly pointed out in 40 the claims.

My invention will be more readily understood by reference to the accompanying drawings forming a part of this specification, and in which—

Figure 1 is an elevation of a lantern embodying my invention.

Figure 2 is a vertical section of the body portion of the same, illustrating portions of the handle and base.

Figure 3 is a sectional view illustrating the switch.

Figure 4 is a side elevation of the top portion of the body, and

Figure 5 is a detail sectional view, upon an 55 enlarged scale, illustrating the manner of mounting the lamp.

Referring now to the drawings, 1 indicates the body portion of the lantern which is preferably a cylindrical metal shell having a bottom 2 and a top closure 3 hinged to the body as at 4 and provided with a spring catch 6 to hold the same in closed position. The spring catch preferably comprises a spring tongue secured in any suitable manner to the closure and having a perforation 65 7 to receive a pin 8 fixed to the body 1. See Figure 4. Fixed to the bottom 2 is a base 9 formed of a suitable wire framework. 10 indicates a handle fixed to the body 1.

The body 1 is adapted to contain a dry-cell battery 11 having the usual carbon electrode 12 and the metal casing 13 thereof constituting the other electrode. Bosses 14 are formed in the bottom of the body 1 upon which the battery rests, and a spring 15 interposed between the closure 3 and the top of the battery holds the latter firmly in position and prevents the same from moving while the lantern is being used for signaling purposes.

Arranged upon the top and bottom of the body 1 are the signal lamps 16 and 17, respectively. These lamps may be of different colors, but are preferably white, and are covered by globes 18 and 19, respectively, 85 one of which may be colored red and the other left white.

Suitable means must be employed for insulating the lamp socket from the body of the lantern, and as the same construction is 90 employed for both the upper and lower lamps, the description of one will be sufficient. To this end, the bottom and top of the body is provided with a preferably centrally-disposed aperture and over the edge 95 of the periphery of the aperture is crimped a metal ring 20 between which and the metal of the body is arranged insulation 21. A socket block 22 is soldered or otherwise secured to the ring 20 and provided with a 100 threaded central aperture 23 to receive the lamp 17 with its end projecting inwardly. The periphery of the block 22 is threaded to receive a ring 24 which engages a base flange on the globe 18 or 19 to hold the same in position. The arrangement is such that when the battery is within the body and the lamps 105 are in position, the end of the lamp 16 will contact the projecting end of the carbon electrode 12 and the end of the lamp 17 will 110 contact the zinc bottom of the battery, as shown clearly in Figure 2. Suitable insula-

tion 25 lines the walls of the body 1. Arranged between the layers of said insulation are flat metal strips forming conductors. The handle 10 is tubular to receive conductors 5 extending from the afore-mentioned conductors to the switch arranged in the upper end of the handle. This switch comprises a pair of contacts 26 and 27 for one of the lamps and similar contacts 28 and 29 for the other 10 lamp. These are supported in any suitable manner by insulation 30. A sliding block 31 is provided within the handle and equipped with armatures 32 to bridge the gap between the respective contacts as will 15 be readily understood. Any suitable form or construction of switch may be employed without departing from the scope of my invention, and I have, therefore, illustrated the switch diagrammatically only. The block 31 20 is provided with a knob 33 projecting through a slot 34 in the handle whereby the switch may be manipulated by the thumb of the hand grasping the handle. 35 indicates one of the conductors in the body portion 25 which extends from the upper block 22 to a conductor 36 extending through the handle to the contact 28, and 37 indicates a similar conductor having one end contacting the zinc shell of the battery, as at 38, and connected 30 with a conductor 39 leading to the contact 29 of the switch. 40 indicates a similar conductor extending from the carbon electrode 12 to a conductor 41 extending to the contact 26, and 42 indicates a similar conductor extending from the lower block 22 to a conductor 43 extending through the handle 10 to 35 the contact 27. By this arrangement it is obvious that if the contacts 26 and 27 are bridged the current will flow from the carbon 40 12 through the conductors 40 and 41 to the contact 26, to 27, through 43 and 42 to the bottom block 22, thence through the lamp 17 to the zinc electrode 13, thus energizing the lamp 17. With the contacts 28 and 29 bridged, the current will flow from the carbon 45 through the lamp 16, upper block 22, conductors 35 and 36, to contacts 28 and 29, thence through conductors 39 and 37 to the zinc electrode at 38.

I claim:—

1. A signal lantern comprising a body, a handle, a pair of signal lamps arranged upon the top and bottom of said body portion, respectively, displaying different colors, a battery within said body, an open frame base 55 for said body, and means for selectively connecting said lamps to said battery, substantially as described.

2. A device as set forth in claim 1 in which the means for selectively connecting the 60 lamps comprises a pair of contacts within the handle for each lamp and a sliding contact within the handle adapted to engage either of said pairs of contacts, substantially as described.

In testimony whereof I have signed my name to this specification in the presence of two subscribing witnesses.

GUSTAVE HUMBER.
